(57) **CLAIM**

The ornamental design for a sausage link maker, as shown and described.

DESCRIPTION

FIG. 1 is a front perspective view of a sausage link maker, showing my new design;

FIG. 2 is a front side view thereof;

FIG. 3 is a back side view thereof;

FIG. 4 is a left view thereof;

FIG. 5 is a right view thereof;

FIG. 6 is a top view thereof; and,

FIG. 7 is a bottom view thereof.

The broken lines of FIGS. 1, 6, and 7 representing placement holes are environmental elements, which form no part of the claimed design.

1 Claim, 5 Drawing Sheets
